CARTON

William P. Frankenstein, Cincinnati, Ohio

Application June 5, 1950, Serial No. 166,207

15 Claims. (Cl. 229—34)

This invention relates to improvements in cartons, and particularly to improvements in knock-down cartons, in which the erected carton is provided with an extending flange from each of the four walls thereof. The invention relates equally to improvements in lids or covers for cartons or boxes and which lid or cover is provided with a flange at the upper ends of the walls.

The disclosure in this application is an improvement on that in applicant's pending application for Carton, Serial No. 592,371, and which was filed on May 7, 1945, now Patent No. 2,514,384, the disclosure in this application accomplishing, in the main, the objects accomplished by the foregoing identified application.

The broad idea of a carton, box, cover or lid having an extending flange in the plane of the panel of the carton or box bottom and the lid or cover covering panel is known, particularly, in the art of set-up boxes. By set-up boxes is meant boxes or cartons which have the walls thereof permanently positioned with respect to the bottom panel and are so formed by the manufacturer for shipment to a user. As was noted above, this application discloses a carton, box, cover or lid which is produced by the manufacturer in a knock-down condition, that is, with the walls folded flat for subsequent erection by the user and which erected carton part has the projecting flange from each wall. In the above identified application certain of the walls have the flange permanently formed by the manufacturer while the flange of the other walls are formed upon erecting the carton and the parts of the flange are held in operative relation by the cooperation of the parts of the permanently attached walls. By the construction disclosed in this application the flanges from each wall are permanently provided for by the manufacturer.

It is, therefore, the principal object of the present invention to provide a knocked-down carton part, that is, the carton or box proper and/or a lid or cover, from each wall of which projects a flange which was permanently provided for during the formation of the carton in its knocked-down condition.

Another object of this invention is the provision of a carton part that is produced in its knocked-down condition to take up a minimum amount of area prior to erection as a full size carton, box, cover or lid.

A further object of this invention is the provision of a carton part which will accomplish each of the foregoing objects and may have either spaced apart or hollow walls or walls of a single or double thickness at each side thereof or some of the walls may be formed of hollow spaced apart members while the others are of single or double thickness.

Specifically, it is also an object of this invention to improve the construction shown in applicant's previously issued Patent Re. 21,158 to provide the carton of said previously issued patent with flanges outwardly of the walls thereof in the plane of the carton bottom.

Other objects and advantages of the present invention should be readily apparent by reference to the following

2

specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is a plan view of a blank partially folded from which a carton of the present invention may be erected.

10 Fig. 2 is a transverse sectional view through a completely folded carton blank showing the same in the condition in which it is shipped to a user.

Fig. 3 is a perspective view of a partially erected carton at an early stage of erection.

15 Fig. 4 is a perspective view of a partially erected carton at a further stage of erection from that of Fig. 3.

Fig. 5 is a transverse sectional view through a fully erected carton as seen from line 5—5 on Fig. 4.

20 Fig. 6 is a plan view, similar to Fig. 1, of a blank showing modifications therein for producing a carton having hollow or spaced apart walls, said blank in Fig. 6 being partially folded.

Fig. 7 is a transverse sectional view through a completely folded or knocked-down carton showing the same in the condition in which it is shipped to the user.

25 Fig. 8 is a perspective view of a partially erected carton from the blank of Fig. 6 with said erection being at an early stage.

Fig. 9 is a perspective view of a partially erected carton 30 at a stage later than that of Fig. 8.

Fig. 10 is a transverse sectional view of a fully erected carton as seen from line 10—10 on Fig. 9.

Fig. 11 is an end elevational view of a fully erected carton from the blank of Fig. 6.

35 Throughout the several views of the drawings similar reference characters are employed to denote the same or similar parts.

As will be noted from the drawings and particularly from Figs. 5 and 10 the modification disclosed in Figs.

40 1 to 5, inclusive, is of a carton, box, lid or cover in which the walls are of double thickness while the modification illustrated in Figs. 6 to 11, inclusive, discloses the same carton, box, lid or cover with the walls of hollow formation or with spaced inner and outer wall members.

45 In general, it is probable that the hollow wall construction would be used for the box proper while the double thickness wall construction would be employed as a lid, also there are numerous instances where both the box proper and lid would be employed with each of the double wall thickness construction. Since both modifications are quite similar in their elements the form in Figs. 1 to 5, inclusive, will be first described in detail and the other modification will be described insofar as the modifications existing therein are concerned.

55 Accordingly, the blank of Fig. 1 comprises a main or bottom panel 15 bounded by score or fold lines 16, 17, 18 and 19 of which score or fold lines 16 and 18 form the sides while the score or fold lines 17 and 19 form the ends of the said main or bottom panel. It is to be under-

60 stood that this nomenclature is used for explanation only since the terms sides and ends are interchangeable depending upon which are the longer with respect to the others. The score or fold lines 16 and 18 respectively, hingedly, connect with the bottom panel 15 similar extensions 20 and 21 which in the erected carton form the side walls. Similarly the score or fold lines 17 and 19, respectively, hingedly, connect with the bottom 15 similar extensions 22 and 23 which in the erected carton form the end walls.

65 70 Since the side wall extensions 20 and 21 are substantially identical in all respects it is deemed sufficient if but one of them be described in detail, extension 20, for ex-

ample. The said extension 20 is provided between its hinging score or fold line 16 and the end of the extension with a plurality of score or fold lines 24, 25 and 26 forming in said extension panels 27, 28, 29 and 30. In the erected carton the panel 27 forms a part of the extending flange and for ornamental effect, as seen in Figs. 3 and 4, has its ends inclined or biased as at 31 and 32. It should be noted that these ends may take any desired contour or may be left to the full length of the carton bottom or cut off to the length of the adjacent panel 28. In the erected carton the panel 28 forms the side wall outer wall member and is of a length of the carton without the extending flanges and is therefore less than the length of the carton bottom and has its ends defined by score or fold lines 33 and 34. The said score or fold lines 33 and 34, respectively, integrally, hingedly, connect to the panel ends tucking flaps 35 and 36. In the erected carton the panel 29 forms the side wall inner wall member, and to all intents and purposes, is of the same length as the panel 28 having its ends in part formed by score or fold lines 37 and 38 and in part formed by cut lines 39 and 40. The cut lines 39 and 40 are inwardly of the score or fold lines 37 and 38 thereby providing shoulders 41 and 42 which, as will later be made clear, form part of the locking mechanism for locking the carton walls in erected positions. The inner wall member or panel 29 has integrally, hingedly, connected to its ends, respectively, through the score or fold lines 37 and 38 tucking flaps 43 and 44. The remaining panel 30 forms a glue flap for securing the lower end of the inner wall member or panel 29 to the main or bottom panel 15.

End wall flaps 22 and 23 being substantially identical in all essential respects, it is deemed sufficient if but one of them be described in detail. Accordingly, extension 22 is provided between its score or fold line 17 and the end thereof with a plurality of substantially parallel score or fold lines 45, 46 and 47 which, in the main, form end wall extension panels 48, 49, 50 and 51. It will be noted that the extension 22, in the main, is of a length equal to the width of the bottom panel 15 as determined between the score or fold lines 16 and 18 while the score or fold lines 45, 46 and 47 are of less length, thereby, providing the panel 48 with end members or arms 52 and 53 that flank the ends of the panel 49 and part of the ends of the panel 50. The ends of the panel 49 are defined by cut lines 54 and 55 thereby making a complete separation of the said panel 49 from the arms 52 and 53 and which panel 49 in the erected carton forms the end wall outer wall member. The portion of the panel 50 that is flanked by the arms 52 and 53 are defined by cut and score lines or lines of perforations 56 and 57 which are readily tearable for a purpose that will presently be made clear. Beyond the arms 52 and 53, the ends of the panel 50 are outwardly formed to provide lugs 58 and 59 which are subsequently used in cooperation with the indented shoulders, 39—41 and 40—42, of the side wall inner wall members in locking the parts in erected positions. The remaining panel 51 is utilized as an additional friction lock or creeper in holding the end walls wall members in erected position.

After the blank has died out as above set forth the carton main or bottom panel 15 is provided in its corners for an area substantially equal to that of the arms 52 and 53 with adhesive, illustrated in the lower right-hand corner of Fig. 1 and indicated by the reference numeral 60, whereupon the end wall extensions 22 and 23 are folded to the position illustrated by the extension 23 at the left-hand end of Fig. 1. The adhesive 60 instead of being applied directly to the main or bottom panel 15 may be applied to the exposed surface of the arms 52 and 53 while in the positions illustrated at the right-hand end of Fig. 1. After the said end wall extensions 22 and 23 have been folded onto the main or bottom panel 15, or prior to said folding, adhesive may be applied to the now exposed surfaces of said arms 52 and 53 and which adhesive

70
75

is illustrated in the lower left-hand corner of Fig. 1 and indicated by the reference numeral 61. At this time the side wall extensions 20 and 21 are each folded on their score or fold line 25 thereby bringing the outer ends of said extensions adjacent the score or fold lines, respectively, 16 and 18 after having applied to the undersurface, for a distance equal, at least, to the length of the end wall flange panel 48, of the glue flaps 30 adhesive 62 and 63 which is brought into engagement with the flange forming panel 27. The folded extensions 20 and 21 are now further and respectively folded on score or fold lines 16 and 18 onto the folded end wall extensions 22 and 23 into the position illustrated by the side wall extension 21, thereby bringing the glue flaps 30 into contact with the end wall extension arms 52 and 53.

Pressure is now applied to the corners, at least, of the folded blank which adhesively secured the arms 52 and 53 to the main or bottom panel 15, adhesively secures one face of the side walls glue flaps 30 to the extension forming panel 27 and adhesively secures the other face of the said side walls glue flaps 30 to the arms 52 and 53 thereby uniting, adhesively, the parts to one another and permanently securing the side wall extension flange forming panels 27 and end walls extension flange forming panels 48 in position. The blank is now in a knocked-down position having each of its end walls extensions 22 and 23 folded to the position of end wall extension 23 and its side wall extensions 20 and 21 folded to the position of side wall extension 21 which would have a transverse cross section as illustrated in Fig. 2.

The user in desiring to set up the carton, box, lid or cover would first raise the side walls from their flat position to an upstanding position which means folding or bending the said walls on the score or fold lines 24 and 26. The end wall extension is then grasped and raised to the position illustrated in the upper end of Fig. 3 and which means the tearing of the cut and score or perforated lines 56 and 57 to separate the end walls wall members from the arms 52 and 53 which are secured below the side walls and particularly beneath the side walls extending flanges panels 27. It will be readily understood that the said arms 52 and 53 being in a secured position retain the panel 48 or the end wall extension flange panel in its operative position and that the upward folding or bending of the end walls takes place on the score or fold line 45.

In erecting the carton both end wall extensions may be torn loose from the arms 52 and 53 prior to the erection of either end of the carton, or after one end wall extension has been released the tucking flaps 35—36 and 43—44 are folded from each side wall to be transversely of the main or bottom panel as illustrated in the upper end of Fig. 3 and with the end wall outer wall member outwardly of the said tucking flaps. In order that this is accomplished the said end wall extension is folded to lie outwardly of the carton as illustrated at the lower end of Fig. 4 prior to the positioning of the tucking flaps whereupon the said end wall is arranged to be normal to the bottom panel. The creeper flap 51 is now folded to be normal to the inner wall member and to project outwardly of the carton whereupon the inner wall member or panel 50 is folded to be interiorly of the carton as illustrated by the upper end of Fig. 4. The parts are locked in their erected position by inserting the locking lugs 58 and 59 of the end wall inner wall member beneath the side wall inner wall member shoulders 41 and 42 and behind the off-set ends of said end walls 39 and 40, or, the said locking lugs 58 and 59 are received in locking notches 64, see Fig. 3, formed at the lower corners of the side wall inner wall members by the said shoulders 41—42 and off-set ends 39—40.

The same steps are now gone through with respect to the remaining end wall whereupon a completely erected carton part, box, carton, lid, or cover, is provided having a main panel with four walls projecting therefrom

and a flange from each wall in the plane of the main, bottom or top covering panel.

It will be noted that by this construction the extending flange from each side of the carton part is permanently produced and that the flanges of the said extensions definitely and positively mark the line for the walls and provide means for permanently positioning the folding line of said walls inwardly of the edges of the main panel.

The foregoing description, as was noted above, pertains to a carton having double thickness walls while the modification disclosed in Figs. 6 to 11, inclusive, discloses a modified carton to the extent that the walls are of hollow construction and include spaced apart inner and outer wall members. The modifications consist essentially in providing a spacer panel or top wall member panel in each of the wall extensions as well as a slight modification in the wall panels for effecting the locking of the walls in their erected positions.

Specifically, the modification consists in modifying the side wall extensions 20' and 21' to the extent of supplying said extensions, respectively, with a panel 65 hingedly connected with the side wall outer wall member or panel 28 through the score or fold line 25 and hingedly connecting with said panel 65 through a score or fold line 66 the side wall inner wall member or panel 29'. As will later be specifically pointed out the end walls are made to a hollow or spaced apart construction thereby further inwardly spacing the end walls inner wall members wherefore the ends of the side walls cannot be conveniently employed for locking the walls in erected position and to supply this omission the said side walls inner wall members 29' are each provided near their outer ends with elongated apertures 67 and 68. The glue flap or panel 30' is enlarged to the extent that it not only projects beneath the extension flange panel 27 but also projects beneath the hollow space between the side walls inner and outer wall members as clearly shown in Fig. 10.

A further modification in the blank of Fig. 6 consists in hingedly connecting to the side walls inner wall members tucking flaps 35' and 36', respectively, through a hinge or fold line 69 and 70 a spacing flap 71 and 72. Each of the spacing flaps is, in the main, of a width substantially equal to the width of the walls top wall members and are adapted to underlie the top wall members of the end walls. For the purpose of ornamentation the free edge of the spacing flaps 71 and 72 adjacent the side walls top wall members or panels 65 are, respectively, provided with an outwardly arcuately shaped bulge 73 and 74. As was noted the said bulges 73 and 74 are supplied for ornamentation purposes and may be readily omitted as far as utilitarian purposes in either assembling or using the carton is concerned. Additionally the extensions 20' and 21' are modified by eliminating from the side walls inner wall members or panels 29' the tucking flaps 43 and 44.

The end wall extensions 22' and 23' are respectively modified by a top wall member or panel 75 which is hingedly connected to the end wall inner wall member or panel 49' by the hinge or fold line 46 with said top wall member or panel 75 hingedly connected with the end wall inner wall member panel 50 by a score or fold line 76. The ends of the end walls outer wall members or panel 49', instead of being formed by a straight cut line 55, are formed by a cut line at each end that is slightly inclined inwardly and contoured or scalloped as at 77 for the purpose of effecting ornamentation at the ends of the carton as clearly illustrated in Fig. 11. It should be noted that the contoured cut 77 may take any configuration insofar as contour is concerned and may also be a straight line at an angle to the longitudinal axis of the blank or may be formed parallel with said blank axis as is the line 55 in Fig. 1.

The ends of the end wall top wall member or panel 75

is illustrated as an arcuate cut at 78 and 79 and which particular formation is again primarily for ornamental purposes since the ends of this panel may be a straight cut line either angled or parallel with the longitudinal axis of the blank. By forming the ends of the end wall outer wall member or panel 49' and top wall member or panel 75 to be generally at an angle to the longitudinal axis of the blank the end wall extension or panel 48 has its arms 52' and 53' somewhat wedge shaped, that is,

- 10 wider at the end where it is integral with the flange or panel 48 than at the free ends thereof which in no wise interferes with the utility of the box or carton nor with its manufacture and erection.
- The blank after being formed is supplied with adhesive and folded as above described for shipment to the user with the end wall extensions 22' and 23' in the folded secured position of end wall extension 23' in Fig. 6 and with the side walls extensions folded and secured in the position of side wall extension 21' in Fig. 6.
- 20 The user in erecting the carton follows the same procedure and steps as above outlined in erecting the carton of Figs. 1 to 5, inclusive. The erected carton of the modification in Figs. 6 to 11, inclusive, results in the corners of the top wall members presenting an ornamental appearance to the extent of a rounded corner effected by the rounded lugs 73 and 74 from the spacing flaps 71 and 72 and the arcuate cuts at the ends of the end walls top wall members or panels 75. The scalloped cuts 77 of the end walls outer wall members or panels 49' give to the erected carton an ornamental end wall effect as illustrated in Fig. 11.

It will be noted that in the modification of Figs. 6 to 11, inclusive, the extending flange is secured in position for each wall requiring the user or erector of the carton to merely set up and lock the side and end walls in operative positions, a construction not heretofore known.

In view of the foregoing, it is believed now evident that there has been provided a carton, box, lid or cover that

- 40 accomplishes the objects initially set forth, and it is to be noted, that while reference in parts of the specification has been made to "carton" or "box" it is to be understood that this term was used for convenience in description and that the construction applies with equal force to a lid or cover.

45 What is claimed is:

1. In a carton part of the class described comprising a main panel, extensions from each edge of said main panel each subdivided by fold lines to provide a carton wall comprising an inner and an outer wall member, each extension including an extending flange forming panel located between its outer wall member and the adjacent main panel edge with said extending flange panel overlying the main panel inwardly of its edge of the main panel, means on certain of said extending flange forming panels 50 projecting therefrom at the ends thereof and underlying the remaining extending flange forming panels and the walls associated with said remaining extending flange forming panels, and means securing the overlying portions of said extending flange forming panels to one another and to the main panel so that said extensions have their wall members articulated to the main panel inwardly of the edges thereof a distance equal to the width of the said extending flange forming panels.

2. In a carton part of the class described comprising a main panel, extensions from each edge of said main panel each subdivided by fold lines to provide a carton wall comprising an inner and an outer wall member, each extension including an extending flange forming panel located between its outer wall member and the adjacent main panel edge with said extending flange panel overlying the main panel inwardly of its edge of the main panel, means on certain of said extending flange panels projecting therefrom at the ends thereof and underlying the remaining extending flange panels and the walls associated with said remaining extending flange forming panels,

means securing the overlying portions of said extending flange forming panels to one another and to the main panel so that said extensions have their outer wall members articulated to the main panel inwardly of the edges thereof a distance equal to the width of the said extending flange forming panels, and means for securing the lower ends of certain of said walls inner wall members relative to the main panel for articulation so that said inner wall members along with their outer wall members are erectable from flat to upstanding positions.

3. In a carton part of the class described comprising a main panel, extensions from each edge of said main panel each subdivided by fold lines to provide a carton wall comprising an inner and an outer wall member, each extension including an extending flange forming panel located between its outer wall member and the adjacent main panel edge with said extending flange panel overlying the main panel inwardly of its edge of the main panel, means on certain of said extending flange panels projecting therefrom at the ends thereof and underlying the remaining extending flange panels and the walls associated with said remaining extending flange forming panels, means securing the overlying portions of said extending flange forming panels to one another and to the main panel so that said extensions have their outer wall members articulated to the main panel inwardly of the edges thereof a distance equal to the width of the said extending flange forming panels, means for securing the lower ends of the inner wall members of two opposed said walls relative to the main panel for articulation relative to said main panel, and tucking flaps from the ends of said two opposed walls which have their inner and outer wall members articulated relative to the main panel disposed transversely of the main panel and enfolded by the inner and outer wall members of the remaining walls.

4. In a carton part of the class described comprising a main panel, extensions from each side of said main panel subdivided to provide walls at each side of the main panel each comprising an inner and an outer wall member, two opposed extensions each, respectively, including an extending flange forming panel located between its outer wall member and the adjacent main panel side overlying the main panel inwardly of its side of the main panel, the remaining opposed extensions each including an extending flange forming panel between its outer wall member and side of the main panel overlying the main panel inwardly of its side of the main panel, tongues from the ends of the last mentioned pair of opposed extensions extending flange forming panels projecting normal thereto to be inwardly of their walls and underlying the extending flange forming panels of the first mentioned pair of opposed wall extensions, means securing the extending flanges forming panels of the first pair of opposed wall extensions and the extending flanges forming panels tongues of the second pair of wall forming extensions to one another and to the main panel so that said extending flanges forming panels are permanently secured in position with the walls inner and outer wall members articulated to the main panel for flat folding and erection normal to the main panel, and means for locking the walls in erected positions.

5. In a carton part of the class described comprising a main panel, extensions from each side of said main panel subdivided to provide walls at each side of the main panel each comprising an inner and an outer wall member, two opposed extensions each, respectively, including an extending flange forming panel located between its outer wall member and the adjacent main panel side overlying the main panel inwardly of its side of the main panel, the remaining opposed extensions each including an extending flange forming panel between its outer wall member and side of the main panel overlying the main panel inwardly of its side of the main panel, tongues from the ends of the last mentioned pair of opposed extensions extending flange forming panels projecting normal thereto to be inwardly of their walls and underlying the extending flange forming panels of the first pair of opposed wall extensions, each extension forming the first mentioned opposed walls, respectively, having a flap at the lower end of its inner wall member disposed between its extending flange forming panel and the tongues, means securing the extending flanges forming panels and flaps of the inner wall members of the first pair of opposed wall forming extensions and the extending flanges forming panels tongues of the second pair of wall forming extensions to one another and to the main panel so that said extending flanges forming panels are permanently secured in position with the walls inner and outer wall members of the first mentioned two opposed extensions and the outer wall members of the last mentioned pair of opposed extensions

ing flange forming panels of the first mentioned pair of opposed wall extensions, means securing the extending flanges forming panels of the first pair of opposed wall extensions and the extending flanges forming panels tongues of the second pair of wall forming extensions to one another and to the main panel so that said extending flanges forming panels are permanently secured in position with the walls inner and outer wall members articulated to the main panel for flat folding and erection normal to the main panel, and means for locking the walls in erected positions, comprising tucking flaps from the ends of two opposed walls enfolded between the inner and outer wall members of the two remaining opposed walls.

6. In a carton part of the class described comprising a main panel, extensions from each side of said main panel subdivided to provide walls at each side of the main panel each comprising an inner and an outer wall member, two opposed extensions each, respectively, including an extending flange forming panel located between its outer wall member and the adjacent main panel side overlying the main panel inwardly of its side of the main panel, the remaining opposed extensions each including an extending flange forming panel between its outer wall member and side of the main panel overlying the main panel inwardly of its side of the main panel, tongues from the ends of the last mentioned pair of opposed extending flange forming panels projecting normal thereto to be inwardly of their walls and underlying the extending flange forming panels of the first pair of opposed wall extensions, each extension forming the first mentioned opposed walls, respectively, having a flap at the lower end of its inner wall member disposed between its extending flange forming panel and the tongues, means securing the extending flanges forming panels and flaps of the inner wall members of the first pair of opposed wall forming extensions and the extending flanges forming panels tongues of the second pair of wall forming extensions to one another and to the main panel so that said extending flanges forming panels are permanently secured in position with the walls inner and outer wall members of the first mentioned two opposed extensions and the outer wall members of the last mentioned pair of opposed extensions articulated to the main panel for flat folding and erection normal to the main panel, and means locking the walls in erected positions.

7. In a carton part of the class described comprising a main panel, extensions from each side of said main panel subdivided to provide walls at each side of the main panel each comprising an inner and an outer wall member, two opposed extensions each, respectively, including an extending flange forming panel located between its outer wall member and the adjacent main panel side overlying the main panel inwardly of its side of the main panel, the remaining opposed extensions each including an extending flange forming panel between its outer wall member and side of the main panel overlying the main panel inwardly of its side of the main panel, tongues from the ends of the last mentioned pair of opposed extensions extending flange forming panels projecting normal thereto to be inwardly of their walls and underlying the extending flange forming panels of the first pair of opposed wall extensions, each extension forming the first mentioned opposed walls, respectively, having a flap at the lower end of its inner wall member disposed between its extending flange forming panel and the tongues, means securing the extending flanges forming panels and flaps of the inner wall members of the first pair of opposed wall forming extensions and the extending flanges forming panels tongues of the second pair of wall forming extensions to one another and to the main panel so that said extending flanges forming panels are permanently secured in position with the walls inner and outer wall members of the first mentioned two opposed extensions and the outer wall members of the last mentioned pair of opposed extensions

articulated to the main panel for flat folding and erection normal to the main panel, and means locking the walls in erected positions, comprising tucking flaps from the ends of the first mentioned two opposed walls enfolded between the inner and outer wall members of the last mentioned opposed walls.

8. In a carton of the class described comprising a main panel, extensions from each edge of said main panel each subdivided by fold lines to provide a carton wall comprising an inner and an outer wall member, each extension including an extending flange forming panel located between its outer wall member and the adjacent main panel edge with said extending flange panel overlying the main panel inwardly of its edge of the main panel, at least two opposed extensions each, respectively, including a top wall member for spacing its inner and outer wall members from one another and a securing flap at the lower end of its inner wall member for articulating the said inner wall member relative to the bottom, means on certain of said extending flange forming panels projecting therefrom at the ends thereof underlying the remaining extending flange forming panels and the walls associated with said remaining extending flange forming panels, and means securing the overlying portions of said extending flange forming panels to one another and to the main panel so that said extensions have their outer wall members articulated to the main panel inwardly of the edges thereof a distance equal to the width of the said extending flange forming panels.

9. In a carton part of the class described comprising a main panel, extensions from each edge of said main panel each subdivided by fold lines to provide a carton wall comprising an inner and an outer wall member, each extension including an extending flange forming panel located between its outer wall member and the adjacent main panel edge with said extending flange panel overlying the main panel inwardly of its edge of the main panel, at least two opposed extensions each, respectively, including a top wall member for spacing its inner and outer wall members from one another and a securing flap at the lower end of its inner wall member for articulating the said inner wall member relative to the bottom, means on certain of said extending flange forming panels projecting therefrom at the ends thereof underlying the remaining extending flange forming panels and the walls associated with said remaining extending flange forming panels, means securing the overlying portions of said extending flange forming panels to one another and to the main panel so that said extensions have their outer wall members articulated to the main panel inwardly of the edges thereof a distance equal to the width of the said extending flange forming panels, and tucking flaps from the ends of said two opposed walls which have their inner and outer wall members articulated relative to the main panel for disposition transversely of the main panel and enfolded by the inner and outer wall members of the remaining walls.

10. In a carton part of the class described comprising a main panel, extensions from each side of said main panel subdivided to provide walls at each side of the main panel each comprising an inner and an outer wall member, two opposed extensions, respectively, including an extending flange forming panel located between its outer wall member and the adjacent main panel side overlying the main panel inwardly of its side of the main panel, said extensions each, respectively, including a top wall member for spacing its inner and outer wall members from one another and a securing flap at the lower end of its inner wall member, the remaining opposed extensions each including an extending flange forming panel between its outer wall member and side of the main panel overlying the main panel inwardly of its side of the main panel, tongues from the ends of the last mentioned pair of opposed wall extensions extending flange forming panels

projecting normal thereto to be inwardly of their walls and underlying the extending flange forming panels of the first mentioned pair of opposed wall extensions, said securing flaps of the inner wall members of the first mentioned two opposed extensions, respectively, being disposed between its extending flange forming panel and the tongues, means securing the extending flanges forming panels and the securing flaps of the inner wall members of the first pair of opposed wall extensions and the extending flanges forming panel tongues of the second pair of wall forming extensions to one another and to the main panel so that said extending flanges forming panels are permanently secured in position with the inner and outer wall members of the first mentioned two opposed wall extensions and the outer wall member of the last mentioned two opposed wall members are articulated to the main panel for flat folding and erection normal to the main panel, and means locking the walls in erected positions.

20 11. In a carton part of the class described comprising a main panel, extensions from each side of said main panel subdivided to provide walls at each side of the main panel each comprising an inner and an outer wall member, two opposed extensions, respectively, including an extending flange forming panel located between its outer wall member and the adjacent main panel side overlying the main panel inwardly of its side of the main panel, said extensions each, respectively, including a top wall member for spacing its inner and outer wall members from one another and a securing flap at the lower end of its inner wall member, the remaining opposed extensions each including an extending flange forming panel between its outer wall member and side of the main panel overlying the main panel inwardly of its side of the main panel, tongues from the ends of the last mentioned pair of opposed wall extensions extending flange forming panels projecting normal thereto to be inwardly of their walls and underlying the extending flanges forming panels of the first mentioned pair of opposed wall extensions, said securing flaps of the inner wall members of the first mentioned two opposed extensions, respectively, being disposed between its extending flange forming panel and the tongues, means securing the extending flanges forming panels and the securing flaps of the inner wall members of the first pair of opposed wall extensions and the extending flanges forming panel tongues of the second pair of wall forming extensions to one another and to the main panel so that said extending flanges forming panels are permanently secured in position with the inner and outer wall members of the first mentioned two opposed wall extensions and the outer wall member of the last mentioned two opposed wall members are articulated to the main panel for flat folding and erection normal to the main panel, and means locking the walls in erected positions, comprising tucking flaps from the ends of two opposed walls enfolded between the inner and outer wall members of the two remaining opposed walls.

12. An end wall construction for a knocked-down carton to provide an extension flange comprising a main panel, an extension from an edge of said main panel integrally, hingedly, connected thereto and subdivided by fold lines to form an outer and an inner wall member with an extending flange forming panel between the outer wall member and main panel, tongues from the ends of the extending flange forming panel flanking the inner and outer wall member, and means securing the tongues to the main panel for securing the extending flange forming panel in overlying position on the main panel inwardly of the hinge connection of the extension thereto.

60 13. An end wall construction for a knocked-down carton to provide an extension flange comprising a main panel, an extension from an edge of said main panel integrally, hingedly, connected thereto and subdivided by fold lines to form an outer and an inner wall member with an extending flange forming panel between the outer

65 14. An end wall construction for a knocked-down carton to provide an extension flange comprising a main panel, an extension from an edge of said main panel integrally, hingedly, connected thereto and subdivided by fold lines to form an outer and an inner wall member with an extending flange forming panel between the outer

70 15. An end wall construction for a knocked-down carton to provide an extension flange comprising a main panel, an extension from an edge of said main panel integrally, hingedly, connected thereto and subdivided by fold lines to form an outer and an inner wall member with an extending flange forming panel between the outer

75 16. An end wall construction for a knocked-down carton to provide an extension flange comprising a main panel, an extension from an edge of said main panel integrally, hingedly, connected thereto and subdivided by fold lines to form an outer and an inner wall member with an extending flange forming panel between the outer

wall member and main panel, tongues from the ends of the extending flange forming panel flanking the inner and outer wall member, and means securing the tongues to the main panel for securing the extending flange forming panel in overlying position on the main panel inwardly of the hinge connection of the extension thereto, said tongues being connected with one of the inner and outer wall members by a weakened line whereby a separation of said wall member may be effected by tearing along the weakened connecting line.

14. A carton part of the class described adapted to be shipped to the user in knocked-down position wherein the carton comprises a main panel, side walls each, respectively, integrally, hingedly, connected to a side of the main panel inwardly of its adjacent edge of the main panel, a flange forming panel overlapping the main panel between each side wall and its adjacent edge of the main panel secured in position over the main panel, end walls inwardly of each end of the main panel, a flange forming panel between each end wall and its adjacent edge of the main panel, tongues from the ends of each end wall flange projecting normal thereto to be inwardly of its wall and underlying the side walls flanges and secured in position, and means temporarily securing each end wall and its end wall flange forming panel tongues to one another while the carton is in its knocked-down condition and which is readily separable for separating the end wall from its flange forming panel tongues for erection.

15. A carton part of the class described adapted to be shipped to the user in knocked-down position wherein the carton comprises a main panel, side walls each, respec-

tively, integrally, hingedly connected to a side of the main panel inwardly of its adjacent edge of the main panel, a flange forming panel overlapping the main panel between each side wall and its adjacent edge of the main panel secured in position over the main panel, end walls inwardly of each end of the main panel, a flange forming panel between each end wall and its adjacent edge of the main panel, tongues from the ends of each end wall flange projecting normal thereto to be inwardly of its walls and underlying the side walls flanges and secured in position, and means temporarily securing each end wall and its end wall flange forming panel tongues to one another while the carton is in its knocked-down condition and which is readily separable for separating the end wall from its flange forming panel tongues for erection, comprising a weakened line of demarcation between the end wall and its end wall extending flange securing tongues.
